[57] CLAIM

The ornamental design for a faucet valve body, as shown and described.

DESCRIPTION

FIG. 1 is a front perspective of a faucet valve body showing our new design;

FIG. 2 is a top plan view thereof;

FIG. 3 is a bottom plan view thereof;

FIG. 4 is a front elevational view thereof;

FIG. 5 is a rear elevational view thereof;

FIG. 6 is a left side elevational view thereof; and

FIG. 7 is a right side elevational view thereof.

The broken line representation of an escutcheon and spout in FIG. 1 is for purposes of illustration only and forms no part of the claimed design.
